CLAIM

The ornamental design for a data transmitter with solar cell and sensor, as shown and described.

DESCRIPTION

FIG. 1 is a front, right, top perspective view of a data transmitter with solar cell and sensor according to our design;

FIG. 2 is a front elevation view of the data transmitter with solar cell and sensor of FIG. 1;

FIG. 3 is a rear elevation view of the data transmitter with solar cell and sensor of FIG. 1;

FIG. 4 is a top plan view of the data transmitter with solar cell and sensor of FIG. 1;

FIG. 5 is a bottom plan view of the data transmitter with solar cell and sensor of FIG. 1;

FIG. 6 is a right side elevation view of the data transmitter with solar cell and sensor of FIG. 1; and,

FIG. 7 is a left side elevation view of the data transmitter with solar cell and sensor of FIG. 1.

The broken lines shown in the drawings illustrate portions of the data transmitter with solar cell and sensor that form no part of the claimed design.
